CAN OPENER

Filed Sept. 10, 1925

FIG 1

FIG 2

FIG 4

John Rogginner

Inventor

By

A. B. Bowman

Attorney

UNITED STATES PATENT OFFICE.

JOHN ROGGINER, OF SAN DIEGO, CALIFORNIA, ASSIGNOR TO NORCO MFG. CO., OF NORCO, CALIFORNIA, A CORPORATION OF CALIFORNIA.

CAN OPENER.

Application filed September 10, 1925. Serial No. 55,489.

My invention relates to can openers and the objects of my invention are: First, to provide a can opener for cutting the head ends out of or the whole ends from metallic hermetically sealed cans, of either cylindrical or rectangular construction; second, to provide a can opener of this class in which the cutter is held in operative relation to the cutter positioning wheel by the supporting handle of the opener, and in which the cutter is automatically removed from its operative position relatively to the cutter positioning wheel, when the supporting handle for the opener is shifted from its normal supporting position; third, to provide a can opener of this class in which the cutter and its driving gear are adapted to be shifted away from and towards the cutter positioning wheel with the axes of the former substantially parallel with the axis of the latter; fourth, to provide a can opener of this class in which the cutter is immediately removed from operative relation with the cutter positioning wheel by a compression spring means when the supporting handle of the opener is shifted angularly with its normal supporting position; fifth, to provide as a whole a novelly constructed can opener for cutting out the heads and wholly removing the head ends of hermetically sealed metallic cans; and, sixth, to provide an opener of this class which is simple and economical of construction, durable, efficient and which will not readily deteriorate or get out of order.

With these and other objects in view as will appear hereinafter my invention consists of certain novel features of construction, combination and arrangement of parts and portions, as will be hereinafter described in detail, and particularly set forth in the appended claims, reference being had to the accompanying drawings and the characters of reference thereon, which form a part of this application, in which:

Figure 1 is a side elevational view of my can opener, showing the same in a cutting position on a can, with the can shown fragmentarily and in section, and showing by dotted lines the cutting member, the cutting member driving gear and the support-

ing handle fragmentarily in certain shifted positions; Figure 2 is a sectional view thereof taken through 2-2 of Figure 1; Figure 3 is an enlarged sectional view thereof taken through 3-3 of Figure 1, and Figure 4 is a fragmentary view of my can opener in a slightly different position relatively to a can adapted to be opened, showing the opener removing the head only of the can, inside of the normally upward extending ledge thereof.

Like characters of reference refer to similar parts and portions throughout the several views of the drawings.

My can opener consists essentially of a frame 1, spindle 2, handle 3, cutter positioning wheel 4, gear 5, plates 6, spindle 7, cutter 8, nuts 9, gear 10, spring 11, supporting handle 12, screw 13, and the collar 14.

The frame 1 is made of a piece of flat metal stock folded over itself, forming a journal 1^a at its folded portion and another journal portion 1^b intermediate its ends, the latter journal portion being semi-circular on one side only and open towards the one end of the frame, as shown best in Figure 2. In the journal 1^a is revolubly mounted the one reduced end of the spindle 2, which spindle is provided at the end extending through the journal with a cutter positioning wheel or disc 4, made of metal, hardened and knurled longitudinally at its face, as shown. On said spindle intermediate its ends and at the opposite end of said journal, is also secured a spur gear 5, which is provided at its opposite sides with tooth guide plates 6. The extended end of the spindle 2 is provided with preferably a flat handle 3 for readily rotating said spindle and a knurled disc 4.

Through the journal portion 1^b of the frame 1 extends a short spindle 7, having its axis parallel with the axis of spindle 2. At the one end of the spindle 7 is secured a circular or disc cutter 8, by means of a nut 9, on the threaded end of the spindle 7. Intermediate the cutter 8, and the one end of the frame 1, is provisioned a collar 14, which is adapted to retain the cutter 8 in a certain position relatively to the outer side of the knurled disc 4, and to

prevent the cutter 8 from riding on the knurled portion of the disc 4. On the opposite end of the spindle 7 is secured a spur gear 10, by means of another nut 9. Said last mentioned gear 10 is adapted when shifted towards the gear 5 to mesh with the latter, and to be driven by the same. The sides of the gear 10 are bevelled slightly at the periphery of the gear so as to permit the teeth of the gears to mesh readily with each other.

Intermediate the normally upper and lower ends of the frame 1 is a hole 1^a which communicates with the semi-circular or cylindrical portion of the journal portion 1^b as shown best in Figures 2 and 3. In this hole is positioned a compression spring 7, which extends into the journal portion 1^b and is adapted to engage the spindle 7 for normally forcing the same outwardly when not using the can opener.

Between the open ends of the frame 1, in which the spindle 7 is mounted, is pivotally mounted, by means of the shoulder screw 13, the supporting handle 12. When the handle 12 is in its normal supporting position for the can opener, the inner end thereof is adapted to engage the normally outer side of the spindle 7 and provide the outer side of the journal therefor, the spring 11 holding the spindle 1 in engagement with the handle 12 and preventing the latter to be readily folded to the dotted line position shown in Figure 1.

The inner end of the handle 12 is preferably made to conform substantially with the contour of the spindle 7, so as to provide a good bearing therefor. It will be here noted that the inner end of the handle 12 extends preferably above and below the horizontal line passing through the axis of the screw 13, so as to hold the handle 12 in a substantially rigid manner, in the supporting position shown by solid lines.

It will be noted that the cutter 8 is beveled at its opposite sides, so as to provide easy cutting of the metal, particularly when desiring to remove only the head of the can, as shown in Figure 4. A cutter beveled only at its outer side will gouge into the side walls of the can.

When desiring to apply the can opener to a can in either of the positions shown in the drawing, the handle 12 is shifted to the dotted line position, as shown in Figure 1, which provides ample space between the cutter 8 and the disc 4 for the reception of the ledge of the can. The handle 12 is then forced to the position shown by the solid lines in both Figures 1 and 4, which forces the cutter 8 to puncture the wall of the can, either at the head or at the side. The handle 12 is then held with one hand and the handle 3 rotated either clockwise or counterclockwise, causing the can to be ro-

tated, by means of the knurled disc 4, against the rotating cutter 8.

Though I have shown and described a particular construction, combination and arrangement of parts and portions, I do not wish to be limited to this particular construction, combination or arrangement, but desire to include in the scope of my invention the construction, combination and arrangement substantially as set forth in the appended claims.

Having thus described my invention, what I claim as new and desire to secure by Letters Patent is:

1. In a can opener, a frame made of flat sheet stock, folded over upon itself, forming two journal portions in its folds, the one of said journal portions being open at one side, a spindle revolvably mounted in said last mentioned journal portion, a cutter secured to said spindle, another spindle revolvably mounted in said other journal portion and provided at its one end with a means for engaging and rotating a can, its periphery being positioned contiguous to the cutting edge of said cutter, and means for rotating said other spindle.

2. In a can opener, a frame made of flat sheet stock, folded over upon itself, forming two journal portions in its folds, the one of said journal portions being open at one side, a spindle revolvably mounted in said last mentioned journal portion, a cutter secured to said spindle, another spindle revolvably mounted in said other journal portion and provided at its one end with a means for engaging and rotating a can, its periphery being positioned contiguous to the cutting edge of said cutter, means for rotating said other spindle, and a handle pivotally mounted between the folds of said frame at the portion of said journal portion open at one end, said handle being adapted to engage at its inner end said first mentioned spindle for holding the cutter mounted thereon contiguous to the can rotating means secured to said other spindle, and for releasing said cutter.

3. In a can opener, a frame made of flat sheet stock, folded over itself, forming two journal portions in its folds, the one of said journal portions being open at one side, a spindle revolvably mounted in said last mentioned journal portion, a cutter secured to said spindle, another spindle revolvably mounted in said other journal portion and provided at its one end with a means for engaging and rotating a can, its periphery being positioned contiguous to the cutting edge of said cutter, means for rotating said other spindle, a handle pivotally mounted between the folds of said frame at the portion of said journal portion open at one end, said handle being adapted to engage at its inner end said first mentioned spindle

for holding the cutter mounted thereon contiguous to the can rotating means secured to said other spindle and for releasing said cutter, and a compression spring positioned between the folds of said frame and extending outwardly into the journal portion open at one side and in engagement with the first

mentioned spindle, for forcing the same outwardly when said handle is shifted to a non-supporting position.

10

In testimony whereof, I have hereunto set my hand at San Diego, California, this 28th day of August 1925.

JOHN ROGGINGER.
